UNITED STATES PATENT OFFICE.

ERNEST L. BAULCH, OF MILLBURN, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed October 9, 1924. Serial No. 742,504.

This invention relates to telephone systems and more particularly to arrangements in long distance or toll line signaling systems.

- 5 In present practice, toll lines may be associated with a plurality of different switchboards and positions at a central office. One switchboard position may be provided for incoming calls while other positions may be 10 provided for outward or through calls. Calls are usually received at the incoming positions and when connections cannot be completed at these positions, it is customary to transfer such calls to any of the other 15 positions depending upon the type of connection desired. Calls intended for through connections are transferred to the through position and delayed inward calls are transferred to the outward position. 20 As to outgoing calls, it is customary for the operator at an "A" operator's position at which such calls may originate, to make use of the service of a recording operator 25 who is reached over a recording trunk and who prepares a ticket bearing the number of the calling party and the number of the wanted party who may be reached over a long distance connection. The recording operator transmits the ticket to an outward toll operator who then selects a toll line 30 leading in the proper direction, and when the operator at the distant end extends the call to the wanted subscriber, this outward operator in turn extends the connection to the calling subscriber through a "B" operator's position as is well known in the art. 35

It is an object of this invention to simplify the extension of outgoing calls over toll lines in systems of the above type for 40 certain kinds of traffic, for example, where the calling subscribers are located in the same exchange and the wanted subscribers may be reached over comparatively short lines, that is, in cases where a large proportion of the calls from the originating exchange are for subscribers in nearby towns or suburbs. It has been found that it is not always practical, in particular for small exchanges, to have their recording operators attend to such short haul traffic. 45 This is due principally to the fact that the cost of such service often exceeds the collectible revenue.

Another object is the provision of a simplified traffic system of this type that is

so designed as to give the maximum flexibility and means for continued growth with the least possible equipment of the more costly kind such as recording operators' position and ticket distributing equipments. 60

To attain these objects in accordance with one feature of the invention, there is provided at certain "A" operators' positions multiple jack extensions for short toll lines by means of which the "A" operators may 65 extend connections over such toll lines directly from local subscribers without the assistance of either a recording operator, an outward operator or a B operator. In some instances it may be advisable to have these 70 multiple jacks at the "A" operators' positions marked or otherwise identified by the name of the towns or suburbs to which the associated toll lines extend or else provide the "A" operators with written instructions 75 as to the terminating points of such toll lines.

Another feature of the invention relates to the provision of means whereby a connection established by an operator over a toll line 80 cannot be interfered with by another operator even though such other operator may disregard the usual busy signal provided for this purpose and attempt to establish a connection by inserting her plug into the 85 jack of the engaged toll line.

Another feature relates to the provision of means for facilitating the transmission of supervisory signals between the operator at a distant end of the toll line and "A" 90 operators connected at the multiple jacks of such toll line.

Another feature relates to the arrangement of these multiple jacks in the circuits of the toll lines in such a manner that the 95 ordinary incoming, through or outward toll operators' jacks are normally connected directly to the toll lines while the multiple jacks are connected only on the insertion of the "A" operators' plugs in such jacks. 100 This arrangement is of advantage in that the circuits for the regular toll line service are normally maintained intact with the least possible intermediate or encumbering switching devices involved. 105

The invention may be more fully understood by referring to the accompanying drawings, in which Fig. 1 represents a preferred form of toll line provided with regular line jacks and a multiple jack 110

equipped in accordance with this invention. Fig. 2 represents a modified form of toll line provided with equipment for performing supervisory functions between the operating 5 at the distant end and the local operator. Fig. 3 shows, in schematic form, a typical layout of the ordinary toll line traffic system and the applicant's invention as applied to such a system.

10 Referring now especially to Fig. 3, the arrangement of the invention as applied to an ordinary toll traffic system will be described. In the case of incoming calls, the inward toll operator at position 1 may receive the call by inserting plug 2 in jack 3 of toll line 4 and after ascertaining the number of the wanted subscriber's line, she inserts plug 5 into jack 6 of a switching trunk 7 leading to a B operator's position 22 and transmits the information to this operator who answers the call by inserting plug 8 into jack 9 of the switching trunk 7. The "B" operator now proceeds to extend the connection to the wanted subscriber by inserting her plug 10 into jack 11 and complete the call to the wanted subscriber 12 in the usual manner. If the incoming call is intended for a subscriber located at a distant exchange, the inward operator transfers the 20 call to the through operator at position 13 and this operator by inserting plug 14 into jack 15 and plug 16 into jack 17 extends the call to the outward trunk 18 leading to a distant exchange; or, if as is the case in delayed or similar types of calls, the inward operator decides to have the outward operator at position 20 attend to the incoming call, the connection is transferred to jack 19 and this operator will thus be notified 30 that her assistance is required.

On the other hand, if an outward connection is desired, the outward operator at position 20, the recording operator at position 21 and the "B" operator at 22 are ordinarily involved in the following manner. In this case, a local subscriber, such as the one located at 25, will connect with an "A" operator at position 26, who after having answered the call by inserting plug 27 in jack 28, ascertains the number of the wanted subscriber at a distant exchange and proceeds to insert plug 29 into jack 30 of a switching trunk 31 leading to a recording operator's position 21. This operator answers by inserting plug 33 in jack 34 and now receives not only the wanted subscriber's number but also the calling subscriber's number from the "A" operator, prepares a ticket 50 containing these numbers and transmits the same through a ticket distributing system, well known in the art to the outward operator at position 20. This outward operator then proceeds to secure a connection to the 60 distant exchange over a toll line such as 4 55

by the use of an order wire well known in the art. When the toll line has been assigned, she inserts plug 35 into jack 19 and completes, by the aid of the operator at the distant exchange, a connection to the wanted 70 subscriber. When the wanted subscriber has been reached, the outward operator inserts plug 37 in jack 38 of switching trunk 39 leading to the "B" operator at position 22 who in turn extends the connection to the 75 calling subscriber 25 and thus the connection with the subscriber at 25 and the wanted subscriber at the distant exchange is completed independent of the "A" operator at position 26 and the recording operator at 80 position 21, which operators are therefore not further concerned with this connection.

It should be noted that this procedure of completing toll connection is rather elaborate and time consuming and when the wanted subscriber may be reached through toll lines leading to nearby towns, the revenue collectible for such connections is comparatively small and in many instances is not commensurate with the cost of the service rendered in extending the connections. Therefore, in accordance with this invention, a number of short toll lines such as 4, leading to surrounding towns to which the traffic is particularly heavy may be equipped with appropriate circuits and multiple jacks at "A" operators' positions. By such an arrangement, local subscribers desiring connections to nearby towns may secure such service without having to wait or to be recalled when a toll connection has been established and the cost of such toll service will therefore be considerably reduced. It would, of course, not be practical to provide such service in all exchanges but rather in exchanges in such cities or towns where the regular long distance traffic is all that can ordinarily be handled by the existing recording operator's equipment and where such traffic may temporarily increase as, for example, would be the case in cities located near seaside resorts or summer colonies to which the toll service would be particularly heavy during the open seasons. In such cities the toll lines leading to these surrounding towns or colonies would be equipped with jacks at "A" operators' switchboards and preferably marked with the name of such places or otherwise identified by the operator so that when outward calls are received for such towns or colonies from a local subscriber such as 25, the "A" operator at 26 may, instead of passing the call to the recording operator at position 21, select a 120 jack associated directly with a toll line leading to such town, for example, jack 40, and thus expedite the service and reduce the cost of handling short haul traffic.

Referring now particularly to Fig. 1 130

which shows an embodiment of the invention as applied to toll line 4, it should be noted that a complete disclosure of the circuits associated with this toll line is shown, 5 that is, for the extension of calls to the inward operator through jack 3 for through service through jack 15, outward service through jack 19 and outward service from the "A" operator's position through jack 40. 10 A detailed description of the functions taking place in this circuit during the extension of these various types of calls will now be made beginning with the reception of a call through the incoming jack 3. In this 15 case, the incoming call over toll line 4 causes the operation of the alternating current responsive relay 50 which closes a circuit for relay 52 as follows: battery, make-before-break contact of relay 53, winding 20 of relay 52, armature and front contact of relay 50 to ground. The operation of relay 52 closes an obvious circuit for relay 54 at its armature and front contact and relay 54, in operating, closes a locking circuit 25 for itself through its left-hand armature and front contact to battery at the make-before-break contact of relay 53. The operation of relay 54 also closes a circuit for busy signals 57 and 58 located 30 respectively at the through and outward operators' positions. This circuit may be traced from battery, right-hand armature and front contact of relay 54, winding of busy signals 57 and 58 in series to ground. The 35 operation of relay 54 also closes a circuit for relay 55 as follows: battery, right-hand armature and front contact of relay 54, inner upper armature and back contact of relay 56, winding of relay 55 to ground. 40 The operation of relay 55, closes at its upper outer armature and front contact an obvious circuit for busy signal 70 associated with multiple jack 40, and closes also at its lower armature and front contact a circuit 45 from battery for the sleeve lead of the multiple jack 40 so as to provide a busy test potential on this jack for the "A" operator in case she should disregard the busy signal 70 and attempt to establish a 50 connection to this engaged toll line by inserting her plug 29 in jack 40. It should also be noted that relay 55, in operating, closes at its inner upper armature and front contact a series contact for an "all busy" signal 55 circuit such as is commonly used in 60 circuits of this type. The lamp 59 at the inward operator's position 1 is also illuminated the moment relay 54 operated over a circuit as follows: battery, make-before-break contacts of relay 53, left-hand armature and front contact of relay 54, right-hand armature and back contact of relay 60, right-hand armature and back contact of relay 61, signal 59 to ground. The inward 65 operator is thus notified that her attention

is required for an incoming call on this toll line.

In answering this call, the inward operator as hereinbefore stated, inserts plug 2 in jack 3, thus completing a circuit for relay 53 as follows: battery, sleeve contacts of plug 2 and jack 3, left-hand armature and back contact of relay 61, left hand armature and back contact of relay 60, winding of relay 53 to ground. The operation of relay 53 at its left-hand armature and back contact breaks the circuit for relay 50 which is normally bridged across the tip and ring leads of toll line 4. This latter relay which may or may not be operated depending on 70 the presence or absence of ringing current on the toll line, will by the release of its armature open the original energizing circuit for relay 52 which in releasing opens the original energizing circuit for relay 75 54, so that relay 53 by operating and in opening the locking circuit for relay 54 at its make-before-break contacts now permits relay 54 to release and extinguish signal 59. It should be noted, however, that the operation 80 of relay 53 provides obvious substitute circuits for maintaining busy signals 57 and 58 and relay 55 operated. It is also clear that the battery supplied at the sleeve of jack 3 will now furnish a busy potential 85 for the sleeves of jacks 15 and 19. The busy conditions established at the through, outward and "A" operators' positions are therefore maintained and controlled by relay 53 until plug 2 is removed from jack 90 3 at the end of the conversation when it releases and returns the toll line circuit to normal.

In case the incoming call on this toll line is intended for a through connection, the inward operator receiving this information transfers the call to the through operator's position at 13 by operating key 62. The operation of key 62 operates relays 54 and 60 over a circuit as follows: battery, right-hand winding of relay 54, right-hand armature and back contact of relay 63, left-hand winding of relay 60 to ground at key 62. The operation of relay 60 breaks the energizing circuit for relay 53 from the sleeve of jack 105 3, restoring this relay to normal, while relay 54 in operating maintains at its right-hand armature and front contact the circuit for busy signals 57 and 58 and through the maintenance of relay 55 energized by this same 110 circuit the busy signal 70 is also maintained operated in a manner that is considered obvious in view of the previous description. It should be noted that lamp 64 associated with the through operator's position 13 will now 115 be lighted over a circuit from battery at the make-before-break contact of relay 53, left-hand armature and front contact of relay 54, right-hand armature and front contact of relay 60, right-hand winding of relay 120 125 130

60 through lamp 64 to ground while lamp 59 is extinguished by the operator of the right-hand armature of relay 60. Relay 60 is now maintained operated through the circuit from battery at relay 53. The operator at the through position 13 now inserts her plug 14 in jack 15 and extends the call through to the distant exchange, as hereinbefore stated, over a toll line such as 18. The insertion of plug 14 in jack 15 now operates relay 53 causing relays 54 and 60 to be released and signal 64 to be extinguished. It should be noted that should the inward operator neglect to release key 62 signal 64 is nevertheless extinguished even though relays 54 and 60 may thereby remain operated. Should the operator find that the incoming call requires the attention of the outward operator at 20 she manipulates key 65 and operations similar to those described for a through connection take place except that relay 61 is operated in place of relay 60 and the outward operator's lamp 66 is lighted in place of lamp 64. In attending to outgoing calls over the toll line 4, under these circumstances the operator at 20 may, by inserting plug 35 in jack 19, close a connection for the tip and ring leads over the toll line as is the usual practice and also establish a sleeve circuit as follows: battery on the sleeve contact of plug 35 of a cord circuit similar to that shown at the right of jack 19, sleeve contact of this jack 19, winding of relay 53 to ground. The operation of relay 53 causes the release of relays 54 and 61 but busy signals 57, 58 and 70 are maintained as hereinbefore described operated from battery at the front contact of relay 53 and lamp 66 is extinguished. In cases where the outward operator originates an outgoing call, that is, without the intervention of the inward operator the procedure is the same except that the insertion of plug 35 in jack 19 will merely operate relay 53 and thereby cause the operation of busy signals 57 and 58 directly and busy signal 70 indirectly by the operation of relay 55 and also establish a busy potential on the sleeve of jacks 3, 15 and 40 as hereinbefore described. If an outgoing toll call can be attended to by the "A" operator without the aid of intermediate operators by extending the connection directly from her position through a multiple jack 40 she inserts plug 29 in this jack and a connection is then established as follows: first, sleeve circuit may be traced from battery, lamp 79, sleeve contacts of plug 29 and jack 40, lower armature and back contact of relay 55, winding of relay 63 to ground. The operation of relay 63 closes a circuit for relay 72 and another circuit for relay 56 from battery through the respective windings of these relays to ground through the left hand armature and front

contact of relay 63. The operation of relay 72 disconnects the tip and ring leads of the inward, through and outward jacks 3, 15 and 19, respectively, which are normally associated with the toll line 4 and completes the talking leads from the jack 40 at the A operator's position to this outgoing end. Relay 72 also closes at its outer lower armature a series connection for the "all busy" circuit hereinbefore mentioned. The operation of relay 56 closes an obvious circuit for the busy signal 70 at its lower armature and front contact and at its upper outer armature and front contact closes an operating circuit for relay 53 and at the same time provides a busy potential at the sleeves of the inward, through and outward jacks. Relay 56 also opens a circuit for relay 55 so that when relay 53 operates this relay cannot become energized which is obviously not necessary in this type of connection. The operation of relay 53 closes a circuit for the busy signals 57 and 58 as hereinbefore described and opens at its left hand armature and back contact the circuit for relay 50. This is to prevent the operation of relays 50, 52 and 54 in this type of connection when ringing current is applied which may be done by the operation of the usual ringing key 80 in the "A" operator's cord circuit.

The inductance in parallel with jack 40 is provided to put a shunt across the tip and ring of the A operator's cord to extinguish supervisory lamp 79 so that the operator will not inadvertently take down the connection during a conversation. In Fig. 2 an inductance of a similar nature is closed across the tip and ring of jack 40 through the contacts of a relay, whereby a more elaborate supervision is provided, as will be explained hereinafter.

In the modified form of the toll line shown in Fig. 2, the results obtained will be the same as with the circuit shown in Fig. 1 and described above. It is identical with the preferred form of the invention, only such changes being made as are necessary for the inclusion of the special supervisory features mentioned above. As far as practical, the same reference numerals have been applied to corresponding parts in the two circuits.

Incoming calls received over this circuit causes relays 50 and 54' to operate in succession. Relay 54' being locked up from the battery at the make-before-break contact of relay 53' causes the lighting of lamp 59. The busy signals 57, 58 and 70 are operated through circuits established at the inner left armature and front contact of relay 54' which also establishes a busy potential on the sleeve of multiple jack 40. When the inward operator answers this call, relay 53' operates and causes the same functions to take place as in the preferred form

when relay 53 operates. Through and outward calls at jacks 15 and 19 also affect the circuit in the same manner as described in connection with Fig. 1 and as the circuits in relation to these operations are easily traced, no further description will be made in this respect.

In extending toll connections directly from the A operator's position, the operation of the circuits is also similar to that described in Fig. 1, that is, relay 63 operates when plug 29 is inserted in jack 40 and the operation of this relay causes the operation of relays 56' and 72. Relay 72 as stated, extends the tip and ring from jack 40 to the toll line 4 and relay 56' establishes the desired busy conditions. Relay 56' also completes a portion of a circuit for supervisory purposes as will hereinafter be described.

When the A operator rings the operator at the outgoing end of the toll line 4, ringing current supplied by the operation of key 80 causes the operation of the alternating current relay 73 which in turn closes an obvious circuit for relay 74 which relay in operating supplies ringing current and ground from source 75 at its armatures and front contacts to the tip and ring lead of toll line 4. This ringing current will be transmitted to the other end of the toll line 4 where it will operate relay 50 which thereupon closes an obvious circuit for relay 76 through the inner lower armature and front contact of relay 56'. Upon the operation of relay 76 a shunt across the tip and ring of the A operator's cord is opened so that the supervisory lamp 79 becomes illuminated. Thus one A operator may signal another. As soon as key 80 is released relays 50 and 76 are released and the bridge across the tip and ring of the cord circuit is closed causing the operation of relay 78 to extinguish lamp 79 as is well known in the art.

If the operator at the distant end decides to call the A operator for the further supervision of the established connection, ringing current is supplied to the toll line 4 from the distant end as is well known in the art, causing the operation of relay 50. As the ringing key of the operator's cord circuit is now released, the operation of relay 50 and the consequent operation of relay 76 and opening of the bridge across the tip and ring of the local jack, causes the release of relay 78 and the lighting of lamp 79. Condensers 82 and 83 are inserted in the tip and ring leads and the circuit in order that relay 50 may operate on the incoming ringing current.

Condenser 84 is inserted in series with relay 73 so that this relay will not operate on battery and ground supplied from the "A"

operator's cord when plug 29 is connected to jack 40.

What is claimed is:

1. In a telephone system, a transmission line terminating in two groups of jacks each at a plurality of positions in a central office, one group normally connected and the other normally disconnected from said line, means responsive to a connection established through the jacks of either group for rendering attempted connections through the jacks of the other group ineffective, a busy signal at several of said positions, a call signal at one of said positions and a ringing responsive means for operating the call signal, for operating the busy signals and for establishing a busy condition on the sleeve of the jack at certain of said positions, means for maintaining said call signal and busy signal operated and the established busy condition effective after the cessation of the ringing, and means responsive to the answering of the call at the position where the call signal is located for releasing said call signal, for maintaining the busy signal operated, for maintaining the established busy conditions effective and for establishing a busy condition on the sleeve of the jacks at the remaining positions.

2. In a telephone system, a transmission line terminating in two groups of jacks each at a plurality of positions in a central office, one group normally connected and the other normally disconnected from said line, means responsive to a connection established through the jacks of either group for rendering attempted connections through the jacks of the other group ineffective, a busy signal at certain of said positions, a call signal at certain of said positions, a ringing responsive means for operating the call signal at one of the positions, for operating all of said busy signals and for establishing a busy condition on the sleeves of the jacks at certain of said positions, means for maintaining said call signal and the busy signals operated and the established busy conditions effective after ringing has ceased, means for releasing the operated call signal and operating any one of the other call signals, means responsive in answering the call at the position where the associated call signal is operated for releasing said call signal, for transferring the control over the busy signals and the established busy conditions to said last mentioned means, for maintaining said busy signals operated and the busy conditions effective and for establishing busy conditions on the sleeve of the jacks at the remaining positions.

3. In a telephone system, a transmission line terminating in two groups of jacks each at a plurality of positions in a central office, one group normally connected and the

other normally disconnected from said line, means for calling from any of the jacks normally connected to the transmission line, means for calling from any of the normally disconnected jacks operative to connect said jacks to the line and disconnect the jacks of the other group from the line, and means responsive to a call from any jack for establishing busy indications at all of said positions.

4. In a telephone system, a transmission line terminating in two groups of jacks each at a plurality of positions in a central office, busy signals at all of the jacks of one

group and at all but one of the jacks of the other group, means for operating said busy signals and for establishing a busy condition at the jack at which no busy signal is located operative when a connection is made through a jack of either group, and means for disabling the jacks of one group when connection is made through a jack of the other group.

In witness whereof, I hereunto subscribe my name this 7th day of October A. D., 1924.

ERNEST L. BAULCH.
